WRINGER RELEASE MECHANISM

Nicholas L. Etten, Waterloo, Iowa

Application May 13, 1937, Serial No. 142,408

2 Claims. (Cl. 68—263)

This invention relates to safety mechanisms for domestic clothes wringers and more particularly to quick release devices for releasing the pressure exerted between the wringer rolls and permitting the rolls to separate. The invention is peculiarly applicable to wringers of the type employing a releasable top frame and wherein the spring or springs for exerting pressure on the rolls is or are carried by or held down by such frame.

A primary object of the invention is to provide a relatively simple and inexpensive mechanism whereby an operator of the wringer, in the case of an emergency, may immediately effect the release of the spring or springs which normally maintain the rolls in close engagement and under relatively high pressure.

Another important object is to provide a quick release mechanism of such character that the top frame and the pressure imposing spring will be restrained against undesirable movements beyond those necessary to effect the release of pressure upon the rolls.

Still another important object is to provide an arrangement whereby certain of the mechanism employed to effect the release of pressure may be used to effect the resetting of the top frame and the resecuring of the spring in pressure exerting relationship with respect to the rolls.

A further object is to provide a simple and inexpensive trigger or the like device of such character and so arranged in cooperative conjunction with a bar or the like extending transversely of the wringer, that the release mechanism may be operated to effect substantially instantaneous release of pressure either by pulling on the bar in a direction away from the wringer or, by pushing on the bar in a direction toward the wringer.

Many other objects as well as the advantages and uses of the invention will be understood and appreciated after reading the following description and claims and after viewing the drawings in which:

Fig. 1 is a front elevation of a wringer mechanism embodying a preferred form of the invention;

Fig. 2 is an end elevation of the wringer shown in Fig. 1;

Fig. 3 is a vertical section of a fragment taken substantially along the line III—III of Fig. 2, the view showing the parts in their normal relationship;

Fig. 4 is a view similar to the view of Fig. 3, but on a slightly larger scale and showing the pressure release mechanism and resetting mech-

anism in a position when the pressure has been released or, in other words, when the parts are in a position for resetting the pressure;

Fig. 5 is a section of a fragment taken substantially along the line V—V of Fig. 3;

Fig. 6 is a section of a fragment taken along the line VI—VI of Fig. 2;

Fig. 7 is a section of a fragment taken along the line VII—VII of Fig. 2; and

Fig. 8 is a fragmentary end elevation of either end of the wringer top frame member, both ends being substantially alike.

The wringer comprises spaced side frame members 2 and 3 joined at their lower ends to the opposite ends of a bottom frame member 4 to which the usual drip aprons 5 may be secured in any suitable and well known manner. Preferably, the side frame members 2 and 3 are made of stamped or pressed sheet metal and are of generally U-shape in cross section. The side frame members carry lower roll bearing blocks 6 which are suitably supported by pins 7 extending through the side frame members and which serve rotatably to support the journals 8 of the lower wringer roll 9. The upper wringer roll 11 likewise has journals 12 bearing in bearing blocks 13 which are mounted for vertical sliding movement in the side frame members. The lower roll 9 may be driven from one end in any suitable manner well understood in the art, and drives the upper roll 11 through its frictional engagement therewith.

A removable top frame member 14 formed of sheet metal and as a single stamping, or otherwise, carries leaf spring 15, the opposite ends of which are arranged normally to press downward upon the bearing blocks 13 in order to press the rolls into engagement with one another, the reaction of the spring being absorbed through the top frame member and by the side frame members when the top frame member is secured to the side frame members. The tension of the spring 15 may be adjusted by a set screw or the like (not shown) by which the spring is secured to the top frame member 14 in an ordinary manner.

Preferably and in the interests of economy and simplicity of manufacture the top frame member 14 is made in one piece and substantially symmetrical with respect to its longitudinal and transverse axes, as will be observed from Figs. 1, 2 and 8. Each end thereof is slotted to provide a slot 16 therein. The upper ends of the side frame members 2 and 3 are designed to be received within the end portions of the top frame

member in telescoping relation therewith and one end frame member, in this instance frame member 3, is provided with one or more lugs 17 struck outwardly therefrom and arranged to pass through slot 16 and to hook over the lower edges of portions 18 of the slot 16. The lug or lugs 17 are designed to permit the top frame member to hinge or pivot thereon or to be released therefrom, as may be desired or as may happen in the functioning of the release mechanism to be described.

Fastened to the opposite end of the top frame member 14 on a rivet or other pin 19 is a U-shaped strap or hinge member 21 which has portions 22 projecting into and through the aperture provided by the slot 16 at this end. Each of the projecting portions 22 is recessed, as at 23, to provide a lip portion 24 which abuts against the outer face of the top frame member adjacent to the edges 18 at this end, thereby the better to 20 secure the hinge member 21, which would otherwise be secured only by the rivet or pin 19.

Hinged on a pivot pin 25 secured in the projecting portion 22 of the hinged member is a reset arm 26 which may be a sheet metal stamping of substantially U-shape in cross section. Normally the reset arm 26 extends downwardly along the side frame member 2 with its lower end in adjacent or abutting relation with the lower end of the side frame member, but when the 25 pressure is released the arm may swing about its pivot 25 to a position such as that illustrated in Figure 4. In order to prevent the top frame member and the spring 15 from flying off in case the top frame member is released from the side frame members, and in order to enable the mechanism to be reset after the pressure has been released, the release is provided with a toggle mechanism which will now be described.

Spaced toggle links 27, which may be formed as a single stamping having an integral joining and spacing portion 28, are pivotally secured at one end of each upon a pivot pin 29 suitably secured in the reset arm 26. The other ends of links 27 are pivoted upon a pivot pin 31 secured in the side frame member 2. The side frame member has a transverse notch or recess 32 adapted to receive the pivot pin 29 when the reset arm 26 lies in adjacent or abutting relation to the side frame member.

As will be noted in Figs. 3 and 4, when the parts are in normal position with the rolls under pressure exerted by the spring 15, and with the reset arm adjacent to the frame 2, a line joining the centers of the pivots 25 and 29 lies to the right of or toward the wringer rolls from the axis or center of the pivot 31. Consequently, the arrangement constitutes an overthrow toggle, so that the force of the spring 15 and its reaction tends to hold the pivot 29 within the recess 32 and the lower portion of the reset arm 26 against the lower side of the side frame member 2. So long as the parts remain in this position with the portions 18 at the opposite end of the top frame engaged beneath the lug or lugs 17, the rolls will remain under pressure determined by the tension on the spring 15. However, if the pivot 29 is moved to the left or away from the rolls to a position where its center lies beyond a dead center position with respect to the center of the pivots 25 and 31, the reaction of the spring 15 will throw the reset arm 26 outward and upward to or above a position such as that illustrated in full lines in Fig. 4.

The mechanism for breaking the toggle, that is

for moving the pivot pin 29 to a position outward beyond a dead center position with respect to a line of centers between the pivots 25 and 31, comprises a lever, or the like, 33, pivoted on a pivot 34 secured between spaced lugs 35 which may be struck from the lower end of side frame member 2 and which, if struck from frame member 2, leave openings through which lever 33 extends. At its outer end the lever 33 is forked to provide projections or lugs 36, normally arranged when the lever is in the position shown in Fig. 3, barely to contact with the inner face of the reset arm 26. At its inner end the lever 33 is provided with a square or other shaped aperture 37 which is adapted loosely to receive the square end 38 of a release bar 39 which extends upwardly and across the front of the wringer. As will be noted from Figs. 2 and 7, there are two levers 33 substantially identical with one another, and two release bars 39, one extending across the front of the wringer rolls and the other across the rear of the wringer rolls. The safety release bars 39, of course, project through suitable apertures in the bottoms of the side frame members 2 and are held in position therein at one end of each by cotter keys, or the like, 41, as will be noted in Fig. 7, and at the other end of each by appropriate means (not shown).

In operation, should an emergency arise during operation of the wringer rolls, as when the person or the clothing of the operator becomes caught in the rolls, a blow or a push upon either safety release bar 39, or a pull upon either of the safety release bars, will rock one of the levers 33 about its pivot 34, which action will cause one of the projections 36 to push the reset arm 26 outwardly and away from the side frame member 2. The outward movement imparted to the reset arm 26 is sufficient to carry the pivot 29 and the lower end of the link 27 outwardly of the notch 32 and away from the side frame member 2 to a position beyond a dead center position with respect to the axes of pivots 25 and 31, whereupon the resultant of the force of the reaction of the spring 15 will carry the reset arm 26 and link 27 upwardly toward and perhaps beyond the position illustrated in full lines in Fig. 4. The outward movement of the reset arm 26, however, is constrained by the link 27, so that the parts may not fly away from their relative association, as might otherwise be the case. Upon release of the reset arm 26 from its normal position, the spring 15 will urge the top frame member 14 upwardly and all tension or pressure upon the rolls 11 and 9 will be released. The action, upon release, is substantially instantaneous.

In resetting the pressure upon the rolls, the edges of portions 18 are reengaged (if they have been disengaged) beneath the lugs 17, and a downward pull upon the resetting arm 26 operates, through the toggle linkage, to recompress the spring 15 and pull the top frame member 14 downward into its proper and normal position. As soon as the pivot pin 29 is reengaged in the recess 32, the wringer is again in operative condition, in which condition it will remain until the pressure release mechanism is again operated.

While I have illustrated and described what is at present a preferred embodiment of the invention, it will be understood and appreciated that the invention is susceptible of embodiment in wringers of different construction and that the reset and release mechanism may take other forms without departing from the spirit of the

invention and the scope of the appended claims.

I claim:

1. In a clothes wringer, a pair of cooperative rolls, resilient means urging said rolls into cooperative engagement with one another, upper and lower frames, releasable latch means connecting the frames on one end, toggle lever release and reset means connecting the opposite ends of the frames, and means to actuate release of said toggle lever including bell cranks attached to the lower frame and inverted U-shaped bars pivotally mounted on each side of the wringer and held outwardly by the roll resilient means for release movement in either direction.

15

2. In a clothes wringer, a pair of cooperative rolls, resilient means urging said rolls into cooperative engagement with one another, upper and lower frames, releasable latch means connecting the frames on one end, toggle lever release and reset means connecting the opposite ends of the frames, inverted U-shaped safety release bars pivotally mounted on each side of the wringer, and dual contact bell cranks each co-acting at plural points with the toggle lever and coacting with the safety release bars to actuate the release of the toggle lever to release roll pressure, and upon reverse movement to reset and hold the safety bars in operating position.
